UNITED STATES PATENT OFFICE.

JESSE LYMAN DANN, OF COLUMBUS, OHIO.

DESIGN FOR AN ELASTIC TIRE.

SPECIFICATION forming part of Design No. 26,338, dated November 24, 1896.

Application filed October 12, 1896. Serial No. 608,656. Term of patent 14 years.

To all whom it may concern:

Be it known that I, JESSE LYMAN DANN, a citizen of the United States, residing at Columbus, in the county of Franklin and State 5 of Ohio, have invented and produced a new and original Design for Elastic Tires; and I do hereby declare the following to be a full, clear, and exact description of the same, reference being had to the accompanying drawings, forming a part thereof.

In the drawings referred to, Figure 1 is a side view of a tire embodying my design. Fig. 2 is a perspective view, on a larger scale, of a portion of the tire, illustrating a cross- 15 section of the same.

The inner side or face *a* of the tire is substantially straight in cross-section, and the sides *b* of the base or inner portion are flat and inclined outwardly from the inner face 20 *a*. The outer portion of the tire, that is, the portion beyond the line *xx*, Fig. 2, is of the general form of an isosceles triangle having its apex *c* rounded and the lower portion of

its equal sides concave or inwardly rounded, as shown at *d*. The lines of the conjunction 25 of the inner or base portion and outer portion are outwardly rounded or convex, as indicated at *e*.

The essential feature of my design consists of the base portion of trapezoid form in cross-section and the outer portion of substantially isosceles form in cross-section with its apex rounded or convexed and the lower portion of its sides inwardly rounded or concaved.

I claim and desire to secure by Letters Patent—

The design for an elastic tire, substantially as herein shown and described.

In testimony whereof I affix my signature 40 in presence of two witnesses.

JESSE LYMAN DANN.
